SIGNAL RECTIFIER CIRCUITS

Seymour Hunt, Jackson Heights, N. Y., assignor to
Radio Corporation of America, a corporation of
Delaware

Application May 6, 1939, Serial No. 272,081

8 Claims. (Cl. 250—20)

My present invention relates to signal rectifier circuits, and more particularly to signal detectors of the carrier degenerative type.

In my copending application, Serial No. 268,078, filed April 15, 1939, (RCA—16,796) there has been disclosed, and claimed, a diode detector circuit which utilizes a driver stage to feed signal energy thereto, and the driver stage being degenerative for the carrier whereby the diode detector may utilize a resistor load of relatively small magnitude. As a result of such construction the diode is capable of handling 100% modulated signals without regard to any loading effect on the tuned circuits feeding the diode detector. Specifically, the driver stage is rendered degenerative in the circuit of the aforesaid application by providing the signal input circuit of the diode detector in the cathode circuit of the stage arranged to function as the carrier degenerative signal transmission tube. The audio voltage component of the diode rectifier circuit was employed in an audio amplifier network following the degenerative stage, while the direct current voltage component was utilized for automatic volume control.

After further investigation of the types of circuits disclosed in my aforesaid application, I have found that the audio voltage component of the rectified carrier energy can be amplified in the carrier degenerative driver stage. In this way the driver stage is given an additional function without in any way interfering with its previously described functions.

Accordingly, it may be stated that it is one of the main objects of my present invention to provide a signal rectification network of the diode type, and wherein the signal input circuit of the diode is provided in the cathode circuit of a stage arranged to function as a carrier degenerative transmission tube, and the audio voltage component of the rectifier output being amplified by the degenerative stage whereby the latter functions as an audio frequency amplifier.

Another important object of this invention is to provide a driver stage for a diode rectifier, the signal input circuit of the rectifier being located in the cathode circuit of the driver, and both the direct current voltage and audio frequency voltage of the rectified signal carrier energy being impressed upon the input control electrode of the driver stage.

Another object of this invention is to provide a signal transmission tube which is degenerative for the signal carrier of received signals, and which feeds carrier energy to at least one diode

rectifier, and the tube feeding the rectifier being fed with the audio frequency voltage output of the latter, the direct current voltage component of rectified carrier energy being utilized for automatic volume control of preceding signal transmission tubes.

Still other objects of the invention are to improve generally the efficiency of operation of diode detector circuits, and more especially to provide a carrier degenerative signal transmission tube capable of feeding signal energy to a diode rectifier, and additionally functioning as an audio amplifier of the rectified signal energy, and the entire arrangement being economically constructed and assembled.

In the drawing:

Fig. 1 illustrates one circuit arrangement embodying the invention.

Fig. 2 illustrates a modification wherein separate diode rectifiers are employed to produce the audio frequency voltage and automatic volume control bias.

Fig. 3 illustrates a modification of the arrangement shown in Fig. 1; and

Fig. 4 illustrates a modification of the arrangement shown in Fig. 3.

Referring now to the accompanying drawing, wherein like reference characters in the different figures designate similar circuit elements, it is assumed that the receiving circuit shown in Fig. 1 is that part of a superheterodyne receiver essential to an understanding of this invention. For example, the numeral 1 may denote the intermediate frequency output circuit of the intermediate frequency amplifier. The receiver can be of the type used in the broadcast range of 550 to 1500 kilocycles, although the invention is equally applicable to multi-range receivers. Of course, the intermediate frequency amplifier may be preceded by the usual converter network, and one or more radio frequency amplifiers may precede the converter. The circuit 1 is magnetically coupled to a resonant circuit 6 which is tuned to the operating intermediate frequency. The circuit 6 functions as the input circuit of the tube 7, and the latter may be a multi-function tube of the 6R7 (or 6Q7) type. In general, such a tube is a duplex diode-triode, and the triode consists of cathode 8, control grid 9 and plate 10. The auxiliary anodes 11, 11' cooperate with cathode 8 to provide a pair of independent diodes. Cathode 8 provides independent electron streams to plate 10 and the anodes 11—11'. Anodes 11 and 11' are strapped together in this arrangement, and function as a single diode anode.

The grid 9 is connected to ground through a path including input circuit 6 and diode load resistor 16; the condenser 17 shunts the load resistor and acts to bypass the intermediate frequency carrier. The cathode 8 is connected to ground through the resonant circuit 13-12. Coil 12 is tuned by condenser 13 to the intermediate frequency. The anodes 11-11' are connected to the grid end of resistor 16. Plate 10 is connected to a source of positive voltage B (not shown) through the audio load resistor 18. The intermediate frequency bypass condenser 19 connects the plate end of resistor 16 to ground, and the audio voltage developed across resistor 18 is transmitted to the subsequent audio stages by audio coupling condenser 20.

The direct current voltage developed across resistor 16 is utilized for automatic gain, or volume, control of the receiver. This is accomplished by connecting the signal grids of the signal transmission tubes prior to tube 7 to the anode end of resistor 16. The lead 21, which includes the filter 22 for suppressing pulsations in the control voltage, connects each prior tube signal grid to the anode end of resistor 16. The lead 21 is designated by the letters "AVC", and those skilled in the art know that the control voltage, or AVC bias, acts to reduce the gain of each prior tube with signal carrier increase to an extent such that the carrier amplitude at input circuit 6 is substantially uniform over a wide range of carrier amplitude variation at the signal collector of the receiver.

The grid 9 is diode-biased in this circuit; that is to say, the direct current voltage across resistor 16 provides the necessary negative bias for the grid 9. With the arrangement shown full gain and selectivity are secured from the circuits 1 and 6. Almost the same amount of carrier voltage appears across input circuit 6 and cathode circuit 13-12. The triode 8-9-10 is degenerative for the intermediate frequency carrier. The carrier voltage developed across tuned cathode circuit 13-12 is applied to the diode anode 11-11'; the rectified current flows through resistor 16 to produce the direct current and audio voltages. The audio voltage appearing across load resistor 16 is applied to grid 9. The triode 8-9-10 now acts as an audio amplifier; the amplified audio voltage appears across output resistor 18.

The diode 8-11 looks into a low impedance, which is equal to the triode plate resistance divided by the mu of the tube plus 1. The input impedance of the triode is substantially infinite. The diode 8-11 may look into an impedance as low as 500 ohms. Hence, the load resistor 16 may be chosen to have a small resistance value. This means that resistor 16 can be chosen for 100% modulation capability without regard to loading of the tuned input circuits. It will now be seen that tube 7 functions as a carrier-degenerative driver for a diode detector and as an audio amplifier without distortion of the audio signal. At the same time the tube provides the required AVC bias for the receiver.

The arrangement in Fig. 2 differs from that of Fig. 1 in that anode 11 is employed to provide the audio voltage for grid 9, as well as the negative bias therefor. However, anode 11' is utilized for providing the AVC bias. Resistor 30, bypassed by intermediate frequency bypass condenser 31, is connected between anode 11' and the negative biasing source 32. The AVC lead 24 is connected to the anode end of resistor 30.

The source 32 provides a delay bias, of any desired value, for the diode rectifier 8-11'.

In Fig. 3, there is shown an arrangement similar to Fig. 2, except that grid 9 receives its negative bias from a biasing source C (not shown) instead of from diode 8-11'. The biasing source is connected to the low potential end of the coil of input circuit 6 through resistor 41. The audio coupling condenser 40 connects the anode end of load resistor 16 to the low potential end 10 of circuit 6. It is to be understood that the circuit is otherwise similar to that shown in Fig. 2; the AVC diode 8-11' and its associated circuit have been omitted.

The space current of triode 8-9-10 may provide the negative bias for the grid 9. It is merely necessary to insert a resistor 50 in series between coil 12 and ground, the resistor being shunted by an audio bypass condenser 51. The resistor 41 is grounded, and thus functions as the direct current voltage connection between grid 9 and the low potential end of biasing resistor 50. The circuit is otherwise similar to that of Fig. 3. It will be noted that the anode 11 is biased by the voltage across resistor 50. This will result in delayed detection by diode 8-11.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In combination, an electron discharge device including at least a cathode, a signal grid and a plate, a source of high frequency coupled to the signal grid, a signal-tuned circuit connected between the cathode and a point of relatively fixed potential, at least one anode operatively associated with the cathode and providing a diode having said tuned circuit as its input circuit, a load resistor connected between the anode and said point, means for impressing on said grid audio voltage developed across said resistor, and an audio load impedance connected to said plate.

2. In combination, an electron discharge device including at least a cathode, a signal grid and a plate, a source of high frequency coupled to the signal grid, a signal-tuned circuit connected between the cathode and a point of relatively fixed potential, at least one anode operatively associated with the cathode and providing a diode having said tuned circuit as its input circuit, a load resistor connected between the anode and said point, means for impressing on said grid audio voltage developed across said resistor, and an audio load impedance connected to said plate, and an automatic volume control connection to said load resistor for utilizing the direct current voltage developed thereacross.

3. In combination, an electron discharge device including at least a cathode, a signal grid and a plate, a source of high frequency coupled to the signal grid, a signal-tuned circuit connected between the cathode and a point of relatively fixed potential, at least one anode operatively associated with the cathode and providing a diode having said tuned circuit as its input circuit, a load resistor connected between the anode and said point, means for impressing on said grid audio voltage developed across said resistor, an audio load impedance connected to 75

5 said plate, a second anode associated with the cathode providing a second diode having said tuned circuit as its input circuit, and an automatic volume control connection to said second diode.

4. In combination, an electron discharge device including at least a cathode, a signal grid and a plate, a source of high frequency coupled to the signal grid, a signal-tuned circuit connected between the cathode and a point of relatively fixed potential, at least one anode operatively associated with the cathode and providing a diode having said tuned circuit as its input circuit, a load resistor connected between the 10 anode and said point, means for impressing on said grid audio voltage developed across said resistor, and an audio load impedance connected to said plate, said load resistor and tuned circuit being arranged in series between the anode 15 and cathode.

5. In a radio receiver system an electron discharge tube provided with at least a cathode, signal grid, plate and auxiliary anode, a signal input circuit connected between the grid and cathode, a second signal input circuit connected between the cathode and ground, a load resistor connected in series between the anode and ground, an automatic volume control connection to the anode end of the load resistor, and means 20 for impressing the audio voltage developed across the load resistor upon said grid.

6. In a radio receiver system, an electron discharge tube provided with at least a cathode, signal grid, plate and auxiliary anode, a signal 25

input circuit connected between the grid and cathode, a second signal input circuit connected between the cathode and ground, a load resistor connected in series between the anode and ground, an automatic volume control connection to the anode end of the load resistor, and means for impressing the audio voltage developed across the load resistor upon said grid, and an audio output resistor connected to said plate for developing thereacross amplified audio voltage. 5 10

7. A signal detector network comprising a signal transmission tube having a tuned circuit connected in its space current path whereby the tube is degenerative for the carrier, a diode rectifier associated with said tuned circuit for 15 providing audio voltage, and means for impressing the audio voltage upon the input electrode of said tube whereby the latter additionally functions to amplify the audio voltage.

8. A signal detector network comprising a signal transmission tube having a tuned circuit connected in its space current path whereby the tube is degenerative for the carrier, a diode rectifier associated with said tuned circuit for 20 providing audio voltage, and means for impressing the audio voltage upon the input electrode of said tube, whereby the latter additionally functions to amplify the audio voltage, and said rectifier additionally developing a direct current 25 voltage, and means for utilizing said direct current voltage for automatic gain control. 30
